UNITED STATES PATENT OFFICE

BERT NOBLE, OF SAN DIEGO, CALIFORNIA, ASSIGNOR TO ROADS CONSTRUCTION COMPANY, LTD., OF LOS ANGELES, CALIFORNIA, A CORPORATION OF CALIFORNIA

ROAD PAVING MACHINE

Application filed November 27, 1929. Serial No. 410,056.

My invention relates to paving machines, particularly to machines for laying concrete or the like upon the roadway, and the objects of my invention are: First, to provide a machine which receives the mixed concrete or other paving material from trucks or from a concrete mixer, spreads it evenly from side to side of the roadway, then tamps it so as to increase the wearing qualities, and then 10 smooths off any irregularities; second, to provide a road making or paving machine which is supported and travels on headers formed along the sides of the roadway; third, to provide a machine of this class which may operate continuously although the paving material is dumped in periodically; fourth, to provide a novel tamping means in connection with a road paving machine; fifth, to provide a road paving machine in which the cut-off 15 and leveler mechanisms and other members which oscillate transversely to the road maintain at all times the proper contact with the paving or roadway so as to insure the proper crown; sixth, to provide a machine of this 20 class which increases the speed of paving; seventh, to provide a machine of this class which requires a minimum amount of skill and labor to operate; eighth, to provide a machine of this class which insures a uniform 25 roadway; and ninth, to provide on the whole a novelly constructed roadway or paving machine which is simple of construction proportional to its functions, durable, efficient in its action, and which will not readily deteriorate 30 or get out of order.

With these and other objects in view as will appear hereinafter, my invention consists of certain novel features of construction, combination and arrangement of parts and portions 35 as will be hereinafter described in detail, and particularly set forth in the appended claims, reference being had to the accompanying drawings and to the characters of reference thereon which form a part of this 40 application, in which:

Figure 1 is a longitudinal, sectional view of my road paving machine, taken substantially through 1—1 of Fig. 3; Fig. 2 is a transverse sectional view thereof, through 45 2—2 of Fig. 1; Fig. 3 is a plan view thereof,

with parts and portions broken away and in section to facilitate the illustration; Fig. 4 is a fragmentary, enlarged, transverse, sectional view through 4—4 of Fig. 1, with parts and portions removed or in elevation to facilitate the illustration; and Fig. 5 is another enlarged, fragmentary, transverse sectional view, through 5—5 of Fig. 1.

Similar characters of reference refer to similar parts and portions throughout the several views of the drawings.

Side members 1, cross members 2, 3, 4, 5, 6, 7, 8, 9, 10 and 11, wheels 12, hopper 13, cut-off member 14, hanger rollers 15, guide rollers 16, cylinder 17, piston 18, piston rod 19, 55 bracket members 20, cylinder 21, piston 22, piston rod 23, tamping beam 24, sleeve brackets 25, rods 26, springs 27, leveler beam 28, cylinder 29, piston 30, piston rod 31, brackets 32, engine 33, compressor 34, air reservoir 35, gear and shaft means 36, air supply pipes 37, control valves 38, clutch lever means 39, and operator's platform 40 constitute the principal parts and portions of 60 my novel road paving machine.

Before using my machine, the roadbed is prepared by grading, surfacing and rolling. Then headers H are positioned along the margins of the road. These form the side 65 margins of the paving which is to be laid upon the roadbed B. The headers are usually wooden beams which are held in place along the margins of the roadbed by stakes or the like, as shown in Fig. 2.

Two side members 1 are provided which 70 are held in spaced relation to each other, one over each margin of the road by cross members 2, 3, 4, 5, 6, 7, 8, 9, 10 and 11. The side members 1 are supported in longitudinal relation, one substantially over each header H 75 by means of wheels 12 which are adapted to roll along said headers H, as shown in Figs. 1 and 3.

The side members 1 are preferably arranged on the outer side of their respective 80 wheels 12 so that the hopper 13, which extends the full width of the roadbed, may be mounted therebetween, as shown best in Figs. 2 and 3. The hopper 13 is mounted adjacent 85 the forward end of the machine just rear-

wardly of the forward wheels. The hopper 13 is not only supported by the side members 1, but also by the cross members 2, 3, and 4. The forward side 13a of the hopper slopes downwardly and rearwardly with a steep enough angle so that concrete or other paving material P, such as an asphalt composition, would readily slide to the bottom of the hopper. The rear side 13b of the hopper extends substantially vertically. The rear side 13b of the hopper does not extend so low as the forward side 13a. Mounted at the rear lower side of the hopper with its lower portion in substantially horizontally disposed relation to the lower edge of the forward side 13a, and its upper margin overlapping the under side portion of the rear wall 13b of the hopper, is a cut-off member 14.

The cut-off member is in the form of a channel iron and is mounted with its base portion in vertically disposed relation to the rear side of the hopper so as to form a continuation of the rear wall thereof. Secured to the forward side of the cut-off member is a forwardly extending lip portion 14a, which extends the length of the cut-off member. As above stated, the lower margin of the cut-off member is flush with the lower margin 13a of the hopper. This lower side of the cut-off member is relatively wide and smooth. The ends of the cut-off member portion extend past the end of the hopper, as shown in Figs. 2 and 3.

The cross member 4, which extends across the rear side of the hopper 13, is in the form of a channel iron with the side walls thereof extending rearwardly. The lower side wall of the cross member 4 forms a track 4a, upon which ride hanger rollers 15, which are connected by suitable hanger brackets 15a to the cut-off member 14, so as to support the weight thereof. As roadways are given what is known as a "crown" or transverse curvature, it is necessary that the cut-off member conform thereto. Thus, the lower margin of the cut-off member is arcuate, having its center of curvature at the same point as the road. The cut-off member is adapted to oscillate transversely to the road. In order to maintain the cut-off member in proper relation to the road at all times, the track portion 4a of the cross member 4 is also made arcuate with its center of curvature at the same point as the roadway, as shown best in Fig. 2.

The cut-off member 14 is prevented from rearward movement by means of guide rollers 16 which engage the rear side of the cut-off member, as shown in Figs. 1 and 2. The guide rollers 16 extend forwardly from the cross member 5. The cross member 5 is secured to the under side of the two side members 1, and extends therebetween in parallel disposed relation to the cut-off member 14.

Secured to the cross member 5, preferably at its central portion, is a cylinder 17, the

longitudinal axis of which is horizontal and extends transversely to the roadway.

Reciprocally mounted within the cylinder, is a piston 17, having a piston rod extending from one or both sides. In the structure shown, there are two piston rods, one extending from each side of the piston. The ends of the piston rod 19 are connected to bracket members 20, which are secured to the rear side of the cut-off member 14. As shown in Fig. 2, the brackets 20 permit a slight vertical movement of the cut-off bar relative to the piston rods 19 so as to permit the cut-off member to follow the transverse curvature of the roadway within the limits of its oscillation.

The cross members 6 and 7 are located in spaced relation to the rear side of the hopper 13. These cross members extend in parallel disposed relation between the upper sides of the side members 1. Mounted in a vertical position, intermediate the ends of, and between, the cross members 6 and 7, is a cylinder 21 having a piston 22 therein, which is adapted to oscillate and cause a like movement of a piston rod 23. The piston rod 23 extends below the cylinder 21 and is secured to the upper side of a tamping beam 24. The beam 24 is made as heavy as possible and extends transversely to the roadway, as shown best in Fig. 4.

The ends of the tamping beam reach to the side margins of the roadway. Secured to the inner sides of the side members 1 is a pair of sleeve brackets 25, each of which is adapted to receive a vertically extending rod 26. The lower edge of each rod 26 is secured to an upper end portion of the tamping beam 24, as shown best in Fig. 4. The upper portions of the rod 26 extend through their respective sleeve brackets 25, and are provided with counter-balancing springs 27, which tend to neutralize the weight of the tamping beam and lift it with the upward movement of the piston.

The piston 22 is adapted to reciprocate the tamping beam in a vertical plane. In order to withstand this movement, the cross members 6 and 7 may be provided with suitable bracing 6a and 7a, as shown in Figs. 1 and 3, but omitted in Fig. 4.

Rearwardly of the rear wheels 12, there is provided a leveler beam 28. This beam is in the form of a relatively thin plate, which conforms to the curvature of the road, and extends between the margins thereof. The beam is adapted to rest by its own weight upon the road.

The cross members 8 and 9 extend between the lower end portions of the side members 1 and are secured to the under side thereof. The cross members 8 and 9 are arranged in parallel disposed relation and support at their central portion a cylinder 29, the axis

of which is horizontal and extends transversely to the roadway.

Reciprocally mounted within the cylinder 29 is a piston 30, which is connected to piston rods 31. The piston rods in turn, are connected at their ends to brackets 32. These brackets 32 extend upwardly from the leveler beam 28. As shown in Fig. 5, the brackets 32 permit slight vertical movement of the leveler beam 28 as said beam follows the curvature of the road in its oscillation.

The cross members 10 and 11 are arranged in parallel disposed relation to each other and extend between the upper sides of the side members 1 just forwardly of the rear wheels 12 and rearwardly of the cross members 6 and 7, as shown in Fig. 1. Supported at the one end of the cross members 10 and 11, is an engine 33. Driven by the engine 33, and also supported by the cross arms is an air compressor 34. A compressed air storage reservoir 35 may also be supported upon these cross members. The engine 33 is connected by suitable gear and shaft means 36 to the several wheels 12, preferably all four wheels so as to give the best possible traction. This may be done, as shown in Figs. 1 and 3, by gearing directly to the front and rear wheels on one side of the machine, which, in turn, are connected by their shafts 12a, to the wheels on the opposite side.

The compressor and reservoir deliver air to supply pipes 37, which connect through valves 38, to the various cylinders 17, 21 and 29. The valves, together with a clutch lever 39 and other controls for the engine 33, may all be arranged so as to be operated from an operator's platform 40 mounted between the cross members 6 and 4, at the one side of the machine, as shown in Figs. 1 and 3.

The operation of my machine is as follows:

The paving material P is poured into the hopper 13. As the machine moves along by reason of the wheels rolling on the headers H, the paving material is caused to flow out the bottom end of the hopper between said headers. During this movement, the cut-off member 14 oscillates back and forth, causing the paving material to work the full distance between the headers, levelling the surface of the paving, and preventing too large a deposit. Simultaneous with this movement, the tamping beam is caused by the cylinder 21 and piston 22 to oscillate in a vertical plane and pound or tamp the paving material firmly so as to pack the various particles thereof into closer bond. At the same time, the leveler beam 28 smooths off any irregularities in the paving caused by the action of the tamping beam. Thus, the pouring, spreading, tamping, and leveling of the paving is all accomplished in practically one continuous operation.

Though I have shown and described a par-

ticular construction, combination and arrangement of parts and portions, I do not wish to be limited to this particular construction, combination and arrangement, but desire to include in the scope of my invention 70 the construction, combination and arrangement substantially set forth in the appended claims.

Having thus described my invention, what I claim as new and desire to secure by Letters 75 Patent is:

1. In a paving machine, a carriage arranged to travel along a roadway prepared for paving, hopper means arranged to deposit paving material upon said roadway, a strike-off member forming a lower margin of said hopper, and means for oscillating said strike-off member transversely of said roadway so as to assist the spreading of the paving material between the margins of said roadway. 80

2. In a paving machine, a carriage arranged to travel along a roadway prepared for paving, hopper means supported thereby and extending between the margins of said roadway, a paving thickness-regulating means forming the one lower margin of said hopper means, the lower margin of said regulating means conforming to the crown of the finished roadway, a track also conforming to the crown of said finished roadway for supporting said regulating means, and mechanism for oscillating said regulating means. 90

3. In a paving machine, a carriage arranged to travel along a roadway prepared for paving, hopper means supported thereby 100 and extending between the margins of said roadway, a paving thickness-regulating means forming the one lower margin of said hopper means, the lower margin of said regulating means conforming to the crown of the finished roadway, a track also conforming to the crown of the finished roadway for supporting said regulating means, mechanism for oscillating said regulating means, leveling means supported by said carriage and conforming to the finished roadway, and mechanism for oscillating said leveling means. 110

4. In a paving machine, a carriage arranged to travel along a roadway prepared for paving, hopper means arranged to deposit paving material upon said roadway, a strike-off member associated with said hopper means for limiting the flow of paving material, separate tamping means spaced rearwardly of said hopper for tamping the paving deposited by said hopper means, and means for leveling said paving material, said means and members supported by said carriage. 115

5. In a paving machine, a carriage arranged to travel along a roadway prepared for paving, hopper means arranged to deposit paving material upon said roadway, a strike-off member forming a lower margin of said hopper, means for oscillating said 125

- strike-off member so as to assist the spreading of the paving material between the margins of said roadway, separate tamping means spaced rearwardly of said hopper for tamping the paving deposited by said hopper means, and an oscillating means for leveling said paving material.
6. In a paving machine, a carriage arranged to travel along a roadway prepared for paving, hopper means supported thereby and extending between the margins of said roadway, a paving thickness-regulating means forming the one lower margin of said hopper means, the lower margin of said regulating means conforming to the crown of the finished roadway, a track also conforming to the crown of said finished roadway for supporting said regulating means, and mechanism for oscillating said regulating means.
- 10 7. In a paving machine, including a carriage arranged to travel along a roadway prepared for paving, and supporting a hopper means, a tamping beam spaced rearwardly of said hopper and extending transversely to and between the margins of said roadway, said tamping beam conforming to the finished roadway and arranged to tamp the paving material deposited by said hopper means, counterbalancing means supporting the ends of said tamping beam relative to said carriage, and operating mechanism for said tamping beam mounted intermediate the ends of said tamping beam.
- 15 8. In a paving machine, including a carriage arranged to travel along a roadway prepared for paving, and supporting a hopper means, a tamping beam spaced rearwardly of said hopper and extending transversely to and between the margins of said roadway, said tamping beam conforming to the finished roadway and arranged to tamp the paving material deposited by said hopper means, resilient counterbalancing means supporting the ends of said tamping beam relative to said carriage, and reciprocating mechanism for said tamping beam mounted intermediate the ends of said tamping beam.
- 20 9. In a paving machine, including a carriage arranged to travel along a roadway prepared for paving, and provided with a hopper means arranged to deposit paving material upon said roadway, a tamping beam supported on said carriage rearwardly of said hopper extending to and between the margins of said roadway, mechanism intermediate the ends of said tamping beam arranged to reciprocate said tamping beam, and counterbalancing means tending to lift said tamping beam from said roadway.
- 25 10. In a paving machine including a carriage supporting a hopper and a tamping beam, a leveling beam positioned at the rear end of said carriage and extending transversely thereof, a cylinder supported on said carriage, a piston within said cylinder, a piston rod extending through each end of said cylinder substantially parallel with said beam, and bracket means connecting the outer ends of each rod with said leveling beam.
- 30 11. In a paving machine including a carriage supporting a hopper and a tamping beam, a leveling beam positioned at the rear end of said carriage and extending transversely thereof, a cylinder supported on said carriage, a piston within said cylinder, a piston rod extending through each end of said cylinder substantially parallel with said beam, and bracket means connecting the outer ends of each rod with said leveling beam, said brackets permitting slight vertical movement of said beam relative to said carriage.
- 35 In testimony whereof, I have hereunto set my hand at San Diego, California, this 15th day of November, 1929.
- BERT NOBLE.
